MIRROR

Lois Gahm, 185 Elmwynd Drive,
Orange, N.J. 07050

Filed June 4, 1970, Ser. No. 23,321

Term of patent 14 years

Int. Cl. D6—07

U.S. Cl. D86—10

FIG. 1

FIG. 2

FIG. 3

FIG. 1 is a rear elevational view of a mirror showing my new design;

FIG. 2 is a front elevational view; and

FIG. 3 is a side elevational view.

The characteristic feature of my invention resides in the specific ornamentation applied to the back of the mirror as shown in FIG. 1.

I claim:

The ornamental design for a mirror, as shown and described.
